PERMANENT WAVE MANDREL

Anthony A. Calabro, New Haven, Conn.

Application April 6, 1944, Serial No. 529,795

5 Claims. (Cl. 132—42)

This invention relates to a novel and improved permanent wave mandrel, that is, a device expressly adapted for use in producing so-called "cold permanent waving" or "finger waving" as the case may be, the same embodying an absorbent pad to be saturated with a suitable hair curling lotion or solution.

Generally speaking, the device is unique in that it differs from others of similar or kindred character and that the hair is curled upon the same, is suspended so that penetration of the lotion or solution used in imparting a permanent or finger-wave to the hair comes not only from the surface, or top as in known types, but from all sides.

Stated more specifically, the preferred embodiment of the invention is characterized by a rigid mandrel of appropriate dimensions and material, the absorbent pad being anchored or otherwise attached to the median portion, and the end portions being provided with special notched adapters to accommodate a flexible cord or equivalent element which is laced back and forth and constitutes an expedient means for caging the pad and wound hair, whereby to effectively sustain the same and to thus achieve the desired aims with efficiency and certainty.

Other features and advantages will become more readily apparent from the following description and the accompanying illustrative drawing.

In the drawing, wherein like numerals are employed to designate like parts throughout the same:

Figure 1 is an elevational view of a permanent wave mandrel constructed in accordance with the specific structural principles of the instant invention, this view showing the wrapping cord loose and the pad still unwound.

Figure 2 is a view like Figure 1 showing the pad wound or reeled in place and the wrapping cord laced and anchored to produce the desired curling results.

Figure 3 is an enlarged central cross-sectional view of the arrangement seen in Figure 1.

Figure 4 is an end view of the mandrel per se with the pad and cords removed.

The mandrel per se may be of any rigid material such as metal, wood, plastic, or whatever composition is found to be appropriate and suitable for usage and varying and other requirements and conditions. It may range in dimensions from less than one inch to more than six inches, and may be, in diameter, one-fourth of

an inch to more than two inches. Essentially, however, it is an elongated body characterized by a reduced central shank 5 provided with enlarged cylindrical heads 6 at opposite outer ends. 10 As brought out in Figure 4, the heads are provided with intersecting kerfs or notches 7 and 8 providing a cruciform or equivalent arrangement of keepers for the free end portion of the wrapping cord or string 9. The absorbent pad, generally 15 of gauze, is of usual rectangular form and dimensions and is denoted by the numeral 10. In practice, this pad may be of any thickness or gauge and made of cotton, silk, linen, fiber, or any equivalent absorbent material. In the instant situation the pad may be said to be of gauze and it is provided at one end with a cross-hem 11 defining a pocket. The pocketed end of the pad is anchored or attached to the mandrel by way of a cord or equivalent loop 12. That is to say, a piece of cord is formed into a loop to provide longitudinal or parallel runs 13 and 14, the end portions of the loop being seated in the adjacent kerfs in the heads 6. The free ends of the cord are knotted or tied together as at 15. 20 The stretch or run 13 passes through the pocket 11 and in this manner fastens the pocketed end of the pad through the mandrel opposite to the reduced shank portion 5. It is thus in position for winding or coiling. A separate cord or an extension of the same cord as that already indicated is the "wrapping" cord 9. As brought out in Figure 3, one portion of this may be extended through the pocket 11 to reinforce the structure, thus leaving the remaining or remainder of the 25 cord free to be laced and wrapped back and forth as shown in the finished arrangement in Figure 2. The use of the series of kerfs at opposite ends makes it possible to lace the cord uniformly and to thus cage-in the pad and strands of hair, in an obvious manner. It is not the purpose of the instant description to cover the technique or to illustrate every phase in a step-by-step manner. I am here concerned primarily with the construction of the mandrel, the manner of 30 attaching the pad by a cord loop or the like to the mandrel and a free wrapping cord which can be suitably laced and portions thereof anchored in the keeper kerfs 7 and 8. 35

In practice, the gauze-pad is, of course, first impregnated or saturated with the customary permanent wave solution as is now customarily done. The pad is then coiled around the mandrel with a lock of hair, from the free ends of 40 the tresses toward the scalp, after which the 45

whole, wound, curl, is secured in place by passing the string 8, which is attached to the mandrel, back and forth and anchoring it in the desired kerfs or slots. This completes the operation, generally speaking.

It is thought that persons skilled in the art to which the invention relates will be able to obtain a clear understanding of the invention after considering the description in connection with the drawing. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. In a permanent wave device of the class described, a rigid mandrel having a central reduced portion and cylindrical heads at opposite outer ends of said reduced portion, said heads having circumferentially spaced keeper notches formed therein, a cord looped and fastened on the mandrel with its runs parallel to the reduced portion, a pad having a hem forming a pocket, said hem being secured to one of said loop runs, and a freely laceable cord attached to said mandrel and cooperable with the keeper notches.

2. In a permanent cold and finger wave curler of the class described, a mandrel having a central reduced portion and cylindrical heads at opposite outer ends of said reduced portion, said heads having keeper notches formed therein, a cord tautly strung and fastened on the mandrel with its runs parallel to and spaced from said reduced portion, a fabric pad secured to one of said runs, and a freely laceable cord attached to said mandrel and cooperable with the keeper notches.

3. In a permanent cold and finger wave curler of the class described, a wooden mandrel having relatively enlarged heads at its opposite outer ends and having its intermediate portion between said heads reduced in diameter and of general concave form, longitudinally extending cords ar-

ranged at circumferentially spaced points around the mandrel and attached to the heads of the mandrel, the intermediate lengths of said cords spanning the central reduced portion of the mandrel and being spaced therefrom, said cords constituting resilient foundation elements around which the hair is coiled, and serving as cushioning means and means for spacing the hair, whereby to permit the waving solution to be uniformly distributed and to permeate the hair windings.

4. In a permanent cold and finger wave curler of the class described, a mandrel having a central reduced portion of cylindrical cross sectional form and heads somewhat enlarged at its outer ends, an absorbent hair winding and curling pad, said pad being adapted to distribute the waving solution to cause it to permeate the hair windings, the convolutions of the pad intervening between the hair windings, and means for yieldably attaching the inner end of the pad to the reduced portion of the mandrel and, at the same time, spacing said inner end from the mandrel, said means constituting the foundation around which the pad is wound, to provide the desired cushioning effect for the pad and to space said pad and hair windings from the mandrel.

5. In a permanent cold and finger wave curler of the class described, a mandrel having a central reduced portion and cylindrical heads at its opposite ends, circumferentially spaced longitudinally extending strands of cord attached to the heads of the mandrel and having their intermediate reaches parallel and spaced from the reduced portion, an absorbent pad attached at its inner end to one of said reaches, the pad being adapted to wind around the reaches to space its convolutions from the mandrel and to provide a resilient foundation for the winding of the pad and hair, and a free cord mounted on said mandrel said free cord being adapted to serve as a retainer to hold the pad wound and the windings of the hair securely in place.
